(57) **CLAIM**

The ornamental design for a bracelet, as shown and described.

DESCRIPTION

FIG. 1 is a top, front and right side perspective view of a bracelet according to our new design;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

Broken lines in the Drawings illustrate portions of the bracelet that form no part of the claimed design. The other broken lines showing text or indicia represent environmental subject matter only and form no part of the claimed design.

1 Claim, 3 Drawing Sheets
